CLAIM

The ornamental design for a gem holder for color evaluating, substantially as shown and described.

DESCRIPTION

FIG. 1 is a top and left front perspective view of a gem holder for color evaluating showing my new design; FIG. 2 is a bottom and right rear perspective view thereof;

FIG. 3 is a top plan view thereof;

FIG. 4 is a front elevational view thereof;

FIG. 5 is a right side elevational view thereof, the left side being a mirror image thereto;

FIG. 6 is a rear elevational view thereof;

FIG. 7 is a bottom plan view thereof; and

FIG. 8 is a cross-sectional view as taken from line 8—8 of FIG. 3.

*FIG. 1.**FIG. 2.**FIG. 3.**FIG. 4.**FIG. 5.**FIG. 6.**FIG. 8.**FIG. 7.*
